UNITED STATES PATENT OFFICE

FRANK JONES, OF WILLIAMSBURG, KENTUCKY, ASSIGNOR OF ONE-HALF TO EVERET F. WHITE, OF WILLIAMSBURG, KENTUCKY

SHOE DYE DRIER

Application filed October 11, 1930. Serial No. 488,127.

This invention appertains to shoe apparatus and more particularly to novel means for drying shoes after the same have been dyed in so-called shoe shining or shoe repairing parlors.

One of the primary objects of my invention is to provide a novel device for effectively drying shoes after the same have been dyed, the apparatus being so constructed as to not only dry the shoes in a minimum amount of time but to also aid in the polish or finish of the shoes being dried.

Another object of my invention is the provision of a device for quickly drying dyed shoes embodying a closed casing for receiving the shoes, with means for heating the closed casing to the desired temperature for bringing about the best results.

Another important object of my invention is the provision of novel means for forming the side walls of the casing, whereby the heat rays from the heating means in the casing will be reflected onto the pair of shoes being dried, whereby not only will the shoes be quickly dried, but also a proper polished finish be imparted to the shoes.

A further salient object of my invention is the provision of novel means for ventilating the closed casing whereby the temperature inside of the casing can be properly controlled.

A still further object of my invention is to provide an improved device for drying dyed shoes of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawings, in which drawings:

Figure 1 is a perspective view of my improved shoe drying apparatus, showing parts thereof broken away and in section.

Figure 2 is an end elevation of the same.

Figure 3 is a longitudinal section through

my improved device taken on the line 3—3 of Figure 2.

Figure 4 is a transverse section through my improved device taken on the line 4—4 of Figure 3 looking in the direction of the arrows.

Referring to the drawings in detail, where-in similar reference characters designate corresponding parts throughout the several views, the letter A generally indicates my improved device, which comprises a closed casing 10.

This closed casing 10 embodies a bottom wall or base 11, longitudinally extending side walls 12, a closed end wall 13, and a top wall 14. The end of the casing 10 opposite to the end wall 13 is closed by a hinged door or the like 15, which is connected by means of a hinge pin 16, with one side wall 12.

The bottom or base 11 is preferably, but not necessarily formed of wood or other material, while the side walls 12, the end wall 13, the top wall 14, and the door 15 is preferably formed of sheet metal, with the inner surface thereof formed of reflecting material, for a purpose, which will be later described.

The casing 10 is adapted to receive shoes, which have been dyed, for the purpose of drying the same and the shoes can be placed into the casing through the door 15, which can be provided with a manipulating handle 16.

The means for heating the interior of the casing 10 can be of any desired nature, but I prefer to use incandescent lamp bulbs 17, owing to the fact that these bulbs will not only give out the desired heat but will also give out light rays which are beneficial to the finish of the shoes. These incandescent bulbs 17 can be screwed into suitable sockets 18 carried by the end wall 13 of the casing 10, the sockets being connected by means of line wires 19 with any suitable source of electrical energy. A control switch 20 can be connected with the top wall 14 for controlling the flow of current to the incandescent lamp bulbs 17.

From the description so far, it can be seen that after shoes have been dyed the same are introduced into the casing 10 and placed on

the base 11, after which the door 15 is closed. The switch 20 is operated so as to close the circuit through the bulbs 17, and the heat from the bulbs being concentrated in the casing will quickly dry the shoes.

5 Further the heat and the light rays emanated from the incandescent lamps 17 will be reflected on the shoes, due to the reflecting surfaces formed on the interior surface of the walls. I have found that not only will this 10 quickly dry the shoes but will also effectively impart a polish thereto.

If preferred, I can provide transparent panes 22 and 23, in the end wall 13 and the door 15, so that the effect of the heat on the 15 shoes can be readily determined by persons looking into the interior of the casing through said transparent panels.

In order to determine the exact temperature in the casing, I can provide a thermometer 24, which thermometer can be inserted 20 through an opening 25 in the top wall 14 of the casing.

The side walls 12 can be provided with 25 ventilating openings 26, which openings can be closed by means of valves or doors 27. I preferably mount all of the doors or valves 30 27 on each side of the casing on a single manipulating rod 28, so that all of the valves or doors 27 can be simultaneously operated. As shown, the rod 28 is in the nature of a 35 shaft and is rockably mounted in bearings 29, which bearings are carried by the opposite sides of the casing. One end of the shaft can be provided with a manipulating handle 30 as shown.

If desired, the top wall 14 can also be provided with ventilating openings 31, and these 40 openings can be closed by pivoted doors or valves 32. These valves or doors 32 can be readily moved over or away from the ventilating openings 31 by means of a handle 33 connected with each one of the same.

If preferred, in lieu of providing the end 45 wall 13 with a sight panel 22, the same can be provided with an elongated ventilating opening, as shown in the drawings, and this opening can be opened or closed by means of a gate or valve 34. As shown, this gate is 50 mounted on a shaft 35, rockably mounted in bearings 36 carried by said end wall. The end of the shaft can be provided with a manipulating handle 37, to permit the convenient rocking of the shaft and the consequent raising and lowering of the door or 55 gate 34.

From the foregoing description, it can be seen that I have provided a novel apparatus, whereby dyed shoes can be quickly and effectively dried and at the same time the desired polish imparted thereto.

In order to further ventilate the casing I can provide the bottom wall or base 11 adjacent to one end thereof with air inlet openings 38, as is shown in the drawings.

Changes in details may be made without departing from the spirit or the scope of this invention, but:—

What I claim as new is:

1. A device of the class described comprising 70 a casing including a bottom, side, end and top walls, one of the side walls being provided with a plurality of openings, a door for closing one of the end walls, drying means mounted within said casing, a manipulating rod supported upon one of said side walls, valves carried by said manipulating rod and adapted to close said opening, said rod provided with angularly bent manipulating handles at the ends thereof for holding said rod 75 against longitudinal movement, said manipulating handles overhanging the ends of said casing and being adapted to engage said door for holding said door in a closed position while said valves are swung to a closed 80 position.

2. A device of the class described comprising 85 a cabinet, heating means mounted therein, said cabinet provided with side walls having a ventilating aperture formed therein, a manipulating rod mounted longitudinally of 90 said side walls and provided with a valve adapted to close said ventilating aperture, brackets for rotatably supporting said manipulating rod, the ends of said manipulating 95 rod being bent angularly to produce manipulating handles adapted to extend across the ends of said cabinet when the valve is moved to a closed position, a door carried by one end of said cabinet and adapted to contact with one of said manipulating handles for assisting 100 in holding said manipulating shaft against accidental movement.

In testimony whereof I affix my signature.

FRANK JONES.
